UNITED STATES PATENT OFFICE.

HIRAM MAINE, OF CHICAGO, ILLINOIS.

SOUND-MUFFLER FOR TELEPHONES.

SPECIFICATION forming part of Letters Patent No. 292,022, dated January 15, 1884.

Application filed May 31, 1882. (No model.)

To all whom it may concern:

Be it known that I, HIRAM MAINE, of Chicago, county of Cook, and State of Illinois, have invented certain new and useful Improvements in a Sound-Muffler for Telephones, of which the following is a description that will enable others to understand and use the same, reference being had to the accompanying drawings, and to letters of reference marked thereon, forming a part of this specification.

The object of this invention is to provide a sound-muffler for telephones, whereby all external sounds and noises are excluded from the ears when using the telephone, thereby enabling the person receiving the message to more readily understand the same, and obviating the necessity of having the message repeated, thus saving much valuable time and avoiding mistakes.

20 The nature of this invention consists, first, in providing the receiver with an elastic and yielding extension which is adapted to conform to the contour of the side of the face and head for the purpose of excluding all outside sounds from the ear; and, second, of a cap or muffler composed of a soft yielding material adapted to cover the opposite ear from the one receiving the message, all as will be hereinafter more fully set forth in detail.

30 Figure 1 illustrates the application and use of my improvement; Fig. 2, a longitudinal section of the receiver and elastic extension; and Fig. 3 is a clamping device used in securing the muffler attachment to the receiver.

35 Referring to the drawings, A represents the telephone-box, B the receiver, C the elastic extension attached thereto, and D the cap for covering the ear opposite from the receiver. The tubular and elastic extension C, attached 40 to the ordinary receiver, is composed, preferably, of rubber; but any other soft, yielding material may be used that would be suitable for the purpose. The end of this extension bearing against the head may be of an irregular contour, if practice so requires, the object being to have the extension of such a size and shape as to completely encircle and thus exclude from the ear all outside sounds. The interior area of this extension may be provided

with adjustable diaphragms, so that the passage may be enlarged or diminished for the purpose of properly modifying the sound coming through the telephone. The extension or muffler C is secured to the receiver by means of the clamping-band a, which is adapted to engage with and encircle the same, as shown in Fig. 2 of the drawings. The joining ends of this open band are provided with the lugs a' a'', and are secured relative to each other by means of the thumb-screw b engaging with the threaded 55 interior of the lugs a''. By this arrangement the extension C can be readily connected to or disconnected from the receiver, as may be required. The cap D is also composed of elastic material, and is conveniently placed with reference to the telephone-box, so that the person using the telephone can rest the side of the head against the same, as shown in Fig. 1 of the drawings. This cap may be adjustably arranged by means of a bracket or similar device; or, if more convenient in practice, the cap may be suspended by a cord and held in the hand of the operator. By this arrangement both ears are protected from external sounds, and the message coming over the telephone-wires will be very distinct, and all confusion avoided.

The present arrangements are such that ordinary conversation in the room and the noise from the street greatly interferes with a proper 80 and distinct understanding of the message.

Having thus described my invention, what I claim as new, and desire to secure by Letters Patent, is—

1. A transmitting and receiving telephone, 85 combined with the elastic muffling-cap D, permanently mounted in position to cover one ear of the operator while standing in proper speaking position before said transmitter, for the purpose set forth.

2. The elastic extension C, provided with internal movable muffling-diaphragms, which may be adjusted to muffle the sounds more or less, as set forth.

HIRAM MAINE.
